[57] CLAIM

The ornamental design for a stiffening tip for a fastening strap for holsters, as shown and described.

DESCRIPTION

FIG. 1 is a perspective view of a stiffening tip for a fastening strap for holsters showing my new design, the portion of a strap being shown in broken lines for illustrative purposes only;

FIG. 2 is a top plan view thereof;

FIG. 3 is a left side elevational view thereof, the opposite side being a mirror image;

FIG. 4 is a bottom plan view thereof;

FIG. 5 is a front end elevational view thereof; and

FIG. 6 is a rear end elevational view thereof.
